UNITED STATES PATENT OFFICE.

SIDNEY D. KRETZER, OF ST. LOUIS, MISSOURI, ASSIGNOR TO ST. LOUIS LIGHTNING ROD COMPANY, OF ST. LOUIS, MISSOURI, A CORPORATION OF MISSOURI.

DESIGN FOR A LIGHTNING-ROD TERMINAL.

42,173.

Specification for Design.

Patented Feb. 13, 1912.

Application filed November 18, 1911. Serial No. 661,179. Term of patent 14 years.

● *To all whom it may concern:*

Be it known that I, SIDNEY D. KRETZER, a citizen of the United States, residing in the city of St. Louis and State of Missouri, have invented a new, original, and ornamental Design for Lightning-Rod Terminals, of which the following is a specification, reference being had to the accompanying drawing, forming a part thereof.

The figure is a perspective view of a lightning rod terminal showing my new design.

I claim:

The ornamental design for a lightning rod terminal, as shown.

In testimony whereof I have hereunto set my hand and signature, this 21st day of October, 1911.

SIDNEY D. KRETZER.

Witnesses:

J. D. RIPPEY,
L. C. KINGSLAND.
